2,369,093

SUPPORT FOR COILED STRIP

Patrick Henry Washam, Jr., Pittsburgh, Pa.

Application September 29, 1942, Serial No. 460,159

5 Claims. (Cl. 242—78)

This invention relates to improved features of structure and arrangement for supporting coiled strip metal while it is being uncoiled prior to its entry between the working rolls of a conventional rolling mill.

More specifically, the improved uncoiler of the present invention includes a pair of opposed carriages movable toward and from one another along a suitable guide, the carriages supporting rotatable heads, each head carrying a plurality of expansible segmental elements adapted to be engaged when in a collapsed position with the central eye or void of a coil of strip metal, and to then be expanded against the action of resilient collapsing means into firm frictional engagement with the eye of the coil.

The uncoilers of the prior art heretofore generally used have had inherent disadvantageous features which may be summarized as follows:

(1) The inner convolutions of the coil are usually loose, and the prior forms of coil supports, when entered in the ends of the coil, have damaged several of the inner convolutions or caused them to be ruptured, resulting in a high scrap loss.

(2) Slippage of the coil on the prior art uncoiler supports is usually prevented by high endwise pressure so that the flanges of the supports are in firm frictional contact with the coil edges. This tends to scarf the edges, and causes high scrap losses.

(3) Due to the crushing of the inner convolutions of the coil by the entrance of the cones of supports heretofore used, the coil is frequently not properly centered on the cones. This results in uneven tension, since the coil does not revolve on its true center in uncoiling.

(4) The supporting cones of prior constructions are unsuited for engagement with coils which frequently are out of round or in bad condition at the core. This results in objectionable delays in starting the uncoiling operation.

(5) The inner convolutions which are frequently damaged by the conical supports of the prior art are difficult to remove after the greater part of the coil has been processed, due to the high pressure applied to hold the coil in place. This results in objectionable delays in making coil changes between uncoiling operations.

The expansible and contractible coil support of the present invention aims to overcome the inherent disadvantages in prior art construction. The novel features of construction and arrangement which constitute the present invention will be fully apparent from the following detailed dis-

closure and the appended claims when read in connection with the accompanying drawings.

In the drawings:

Figure 1 is a view partly in elevation and partly in section, illustrating supporting means for coiled strip embodying the claimed invention.

Figure 2 is an end elevation of one of the main component elements of the improved coil support.

Figure 3 is an enlarged vertical section taken on line III—III of Figure 1.

Figure 4 is a fragmentary detail view of a portion of rotatable head and an expansible segmental element constituting an essential element of the invention.

Figure 5 is a section taken approximately on the staggered line V—V of Figure 3.

Figure 6 is a detail view of the rotary supporting head showing the fulcrum sockets for supporting the expansible segmental elements.

Figure 7 is an elevation viewed from the right end of Figure 6.

Figure 8 is a detail view of a spring anchorage unit adapted to be secured to the rotating head.

Figure 9 is a section on line IX—IX of Figure 8.

Figures 10 and 11 are plan views of fragmentary portions of two adjacent expansible segmental elements equipped with interengaging means effective to couple the several segments as an integrated circular unit.

Figure 12 is a detail view of a portion of one of the segmental elements as viewed on line XII—XII of Figure 10.

Referring in detail to the drawings, the numerals 10—10 represent a pair of carriages slidably supported on a suitable base 12 and adapted to be moved toward and from one another by means of a feed screw having respective right- and left-hand threaded portions 14 and 16 passing through nuts 18 secured to the carriages 10. Since the oppositely disposed supporting devices are of identical construction, a description of one will suffice for both. The duplicate parts are identified by corresponding reference numerals. The feed screw can be operated by feed wheel 20, or can be connected to a suitable power driven gear.

Shafts 22 are rotatably supported in roller bearings 24 in the carriages 10, and have heads 26 formed integrally on or otherwise secured thereto. These heads form the main supporting means for the improved coil-supporting devices. Bolted or otherwise secured to each head 26 is a flanged ring 28 having a wear ring 30 adapted to confine the edges 31 of the coil of

strip metal which is to be uncoiled while supported on the device of the present invention.

A central hub portion 32 of each rotatable head 26 has a plurality of fulcrum sockets 34 formed therein. In the embodiment illustrated there are four such sockets, and each is lined with a semi-cylindrical shell 36 of antifriction bearing metal.

A plurality of expandable segmental elements 38 are provided, each having a respective knuckle portion 40 rounded at its inner extremity so as to engage with and fulcrum on the lining shell of the fulcrum socket. The segmental elements 38 each comprise a portion 42 corresponding to the surface of a cylinder and inner and outer portions 44 and 46 corresponding to the surfaces of respective cones which merge into the surface of the cylindrical portion 42.

A plurality of arcuate holding and separator bars 48 are positioned at equally spaced intervals around the head by pins 50, and are secured thereto by bolts 52. These bars flank the opposite portions of the knuckles 40, as clearly shown in Figure 3, and serve as a rigidifying means for the pivotally mounted segmental elements.

In the embodiment of the invention illustrated, the expandable portion of the support comprises four segmental elements, but I am not limited to this number, as any desired number of circularly arranged parts may be employed. The segmental elements when in the expanded position of Figure 1 jointly form a complete cylinder in the region of the cylindrical portion 42, and jointly form an interrupted cone in the inner region of the conical portions 44. The several collapsing springs 54 are anchored at their outer ends to ribs 56 formed on the segmental members, and at their ends to lugs 58 formed on a spring-anchorage unit 60 which is secured to the head 26 by bolts 62, as shown in Figure 2. This anchorage unit is recessed at 64 (Figure 9) to accommodate a cover plate 66 which serves as a guard or cover for the several springs.

Retainer brackets 68 are secured to the head 26 by suitable bolts 70 which engage the central hub extension 32 of the head. These retainer brackets, as best shown in Figure 3, are provided with pintle extensions 72 engageable with apertures 74 formed in the knuckles 40. The pintle extensions 72 make a relatively loose fit with the apertures 74, so as to permit the main bearing load on the segments to react against the fulcrum sleeves 36 positioned in the sockets 34.

A plurality of radial grease ducts 76 are formed in the hub extension 32. These connect with a central duct 78, the outer end of which is threaded to receive a conventional form of grease cup. The knuckles are provided with grease passages 80, and suitable openings are formed in the bearing shells 36 to permit the passage of lubricant to the pintle pins 72.

The several segmental elements are integrated with one another as a circular unit when in collapsed position, by dowels 82, 84 and 86, each dowel being fixedly secured to one segmental element and make a sliding fit with the notches 88 and 90 in mating elements adjacent thereto. When the segments are moved to the collapsed position of Figures 4 and 11, the dowels 84 and 86 tightly engage the sockets 88 and 90 formed in the respective opposed radial faces of the mating segments. Thus it is apparent that the several segments are integrated as a circular unit in expanded position by the dowels 82 and are similarly integrated as a unit in collapsed position by the joint action of all three dowels

82, 84 and 86. This interlocking arrangement in both expanded and collapsed position serves to axially align the combined segmental elements of the expandable coil-engaging member with the central axis of the coil of strip material.

In the operation of the improved supporting means illustrated, it will be understood that in order to initially engage the collapsible members with the coil of strip material, the carriages 10-10 will be retracted to positions to permit insertion of the coil between them. When the carriages are thus retracted, the several springs 54 will rock the segmental elements inwardly about their fulcrum supports to the collapsed positions such as shown in dotted lines in Figure 1 and full lines in Figure 4. In this position the inner conical portions 44 of the thus-collapsed segmental elements can be readily entered into the innermost central void or eye of the coiled material which is represented by the dot-and-dash line *a* in Figure 1. Thereupon the feed screw will be operated to cause the carriages 10-10 to approach one another. This will cause the segmental elements to rock on their fulcrums 40, thus expanding the elements and exerting a very forceful friction grip. In so doing, the eye of the core will be expanded, for example, to the position indicated by the dot-and-dash line *b* in Figure 1. If greater frictional drag on the coil is desired, the carriages can be caused to more closely approach one another, whereupon the conical portions 46-46 will be wedged into the eye or central void of the coil. This arrangement provides means for exerting a tremendous strip tension, as will be readily apparent from examination of the drawings. In practice it has been found that apparatus such as that shown and described can expand the inside diameter or eye of a coil of strip material from about 18 $\frac{1}{2}$ inches to about 20 $\frac{1}{4}$ inches. The apparatus is of rugged construction and is so constructed and arranged that the parts cannot readily be damaged, yet coil changes can be conveniently and quickly made in the minimum amount of time and with a minimum of damage to the eye and edge portions of the strip. This materially cuts down scrap losses, and results in important operating economies in the uncoiling of strip material as the material is fed to the working rolls of the rolling mill or to any other apparatus.

While I have described quite specifically an embodiment of the invention which an actual reduction to practice has demonstrated is highly desirable, it is not to be construed that I am limited thereto, since various modifications and substitutions of equivalents may be made by those skilled in the art without departure from the invention as defined in the appended claims.

I claim:

1. Supporting means for coiled strip material, comprising a pair of opposed carriages movable toward and from one another, rotatable heads journaled thereon each having a plurality of fulcrum sockets formed therein, segmental coil-supporting elements having knuckles seated in said sockets, springs anchored to said elements tending to rock them inwardly about said fulcrum sockets, and retainers secured to said heads having a pivotal connection with said knuckles.

2. Supporting means for coiled strip material, comprising a pair of opposed carriages movable toward and from one another and rotatable heads journaled thereon each having a plurality of fulcrum sockets formed therein, segmental coil-

supporting elements having knuckles seated in said sockets, springs anchored at their outer ends to said elements, an anchorage secured to the head for engagement with the inner ends of said springs, and retainers secured to said heads having a detachable pivotal connection with said segmental elements.

3. Supporting means for coiled strip material, comprising a rotatably mounted member having movably supported thereon a plurality of cone-like segments adapted to be expanded outwardly into engagement with the central eye of a body of coiled strip, said segments being fulcrumed on said member and one set of coacting means coupling said segments together as a circular unit when they are in expanded condition and another set of coacting means coupling said segments together as a circular unit when they are in collapsed condition, each of said coacting means including an element secured to and projecting from one of said segments and a recessed portion formed in a coacting segment.

4. Supporting means for coiled sheet metal, comprising a rotatably mounted head, a plurality of segments pivotally associated therewith, each segment having respective outer coil-engaging portions corresponding to the surfaces of a cylin-

der and a cone, springs normally tending to rock said segments inwardly, one set of coacting means coupling said segments together as a circular unit when they are in expanded condition and another set of coacting means coupling said segments together as a circular unit when they are in collapsed condition, each of said coacting means including an element secured to and projecting from one of said segments and a recessed portion formed in a coacting segment.

5. Supporting means for cooled strip material, comprising a rotatably mounted member having a plurality of segments pivotally mounted thereon, each segment having portions corresponding to the surfaces of respective cylinders and cones, springs tending to rock said segments about their pivotal supports, and one set of coacting means coupling said segments together as a circular unit when they are in expanded condition and another set of coacting means coupling said segments together as a circular unit when they are in collapsed condition, each of said coacting means including an element secured to and projecting from one of said segments and a recessed portion formed in a coacting segment.
